(57) **CLAIM**

The ornamental design for a comb holder, as shown and described.

DESCRIPTION

FIG. 1 is a top perspective view of the comb holder of the present invention;

FIG. 2 is an overhead view of same;

FIG. 3 is a front view of the comb holder of FIG. 1, the rear view being identical;

FIG. 4 is a right side view of same, the left being identical; and,

FIG. 5 is a bottom view of the comb holder of FIG. 1.

The material shown in broken lines is provided for environment only and is not considered part of the claimed invention.
